[57] CLAIM

The ornamental design for a shower head, as shown and described.

DESCRIPTION

FIG. 1 is a bottom, front perspective view of a shower head or the like showing my new design; and,

FIG. 2 is a front elevational view thereof, the right side, left side, rear elevational views all being identical.

FIG. 1

FIG. 2

FIG. 3

FIG. 4

UNITED STATES PATENT AND TRADEMARK OFFICE
CERTIFICATE OF CORRECTION

PATENT NO. : Des. 328,944

DATED : August 25, 1992

INVENTOR(S) : Tom E. Robbins

It is certified that error appears in the above-identified patent and that said Letters Patent is hereby corrected as shown below:

Delete the present description of the figures and replace it with:

--Fig. 1 is a bottom, front perspective view of a shower head or the like showing my new design;

Fig. 2 is a front elevational view thereof, the right side, left side, rear elevational views all being identical;

Fig. 3 is a top plan view thereof; and

Fig. 4 is a bottom plan view thereof.--

Signed and Sealed this

Twenty-fourth Day of August, 1993
